(57) **CLAIM**

The ornamental design for a roller blind tube as shown and described.

DESCRIPTION

FIG. 1 is an upper side perspective view of the roller blind tube of the present design.

FIG. 2 is a right end view thereof.

FIG. 3 is a front view thereof.

FIG. 4 is a rear view thereof.

FIG. 5 is a top view thereof; and,

FIG. 6 is a left end view thereof.

The break lines symbolize breaks in the length of the article in which the claimed design is embodied. The appearance of any portion of the article between the break lines forms no part of the claimed design.

1 Claim, 6 Drawing Sheets
